ATTORNEYS

UNITED STATES PATENT OFFICE.

STANLEY B. MATHEWSON, OF SPRINGFIELD, AND WALTER K. JAMISON, OF DAYTON, OHIO, ASSIGNEES TO STANLEY B. MATHEWSON, WALTER K. JAMISON, HOWARD F. MARSTON, (MRS.) S. B. MATHEWSON, AND (MRS.) W. K. JAMISON, TRUSTEES, OF THE LECAR CARBON COMPANY, A TRUST ESTATE, OF SPRINGFIELD, OHIO.

RETOFT.

Application filed February 15, 1924. Serial No. 693,058.

Our invention relates to an apparatus for converting certain raw materials into carbonizing materials and collecting the by-products, or utilizing them.

5 Our invention has for its object the rapid and economical handling of such material as scrap leather when treating it to convert it into a carbon material containing certain volatile gases. This material is used for case 10 hardening metals, filtering oils and sugars, and a variety of other applications. It is more fully set forth and described in our Patent No. 1,471,563 of October 23, 1923.

It is a further object of our invention to 15 provide means of uniformly treating the scrap leather with heat, of preventing the access of air thereto during the heating operation, of conveying away such gases that are generated, of retaining the gases in the material or in the presence thereof, and of permitting the reabsorption of such gases so retained as the material cools.

It is a further object to provide means of 20 readily handling in easily managed units the containers for such material. It is an object to provide means by which the containers can be accommodated to the amount of material.

It is a further object to provide means of 25 safely conveying the gases away from the oven to a point where the by-products can be abstracted or the gases used for fuel purposes, or both.

Referring to the drawings:

Figure 1 is a plan view of the oven and 30 stacks with the cover of the oven removed.

Figure 2 is an end elevation of the oven with the front wall removed.

Figure 3 is a side elevation of the oven and the containers with the side wall removed.

Figure 4 is the detail of the tops of the containers and the pipe connections.

Figure 5 is an end elevation of one of the containers.

Figure 6 is a side elevation of one of the containers.

Fig. 6^a is a detail view of a clamp in posi-

tion for clamping the container's ends together.

Figure 7 is a plan view of the truck for 50 supporting and transporting the containers.

Figure 8 is a side elevation of the truck.

Figure 9 is an end elevation of the truck. Figure 10 is a side elevation of the furnace with the side wall removed.

55 Referring to the drawings in detail:

1 is a front wall of the oven, 2 and 3 are the side walls, and 4 is the rear wall. Adjacent to the rear wall is the furnace compartment 5 shown in elevation in Figure 10. This furnace is provided with furnace doors 6 and the furnace wall 7 for the introduction of fuel therein. Any furnace of conventional character may be employed so that the heat from the furnace may pass upwardly over the baffle 60 wall 8, through the opening 9, into the oven compartment 10, beneath the roof 11. The heat from the furnace passes through the oven around the containers to the remote end of the oven, at which point it passes downwardly into the flue 12, beneath the floor 13 of the oven and thence into the passageway 14 and up the stack 15. This arrangement is such that the heat must pass completely 65 around all of the containers, uniformly treating all of them. The passageways 12 are provided on either side of the oven so that there will be an even exit and distribution of the heat.

70 The scrap leather is placed in the containers 16 and these containers are placed on end upon the trucks. The trucks are composed of channel members and I-beams, forming a frame designated 17. On the frame are angle irons 18 to prevent lateral movement of the containers on the truck. A running gear consisting of the axles 19 and the flange wheels 20 is provided.

75 The containers are then wheeled into the ovens and have connected to vents 21 the vertical pipes 22 and T or L-shaped couplings 23. These couplings are connected in turn to branch pipes 24, which are united to the main pipes 25. These main pipes 25 are conveyed at right angles as at

80 85 90 95

26 through the side walls of the ovens out of the ovens, so that the by-product gases may be scrubbed, chemically treated, and finally used, if desired, as fuel in the furnace 5 of the oven, or for a similar purpose.

The containers are provided with mid-ribs or flanges 27 which are clamped together as by clamps 27^a having the screw bolts 27^b for tightly holding the flanges together.

10 It will thus be seen that our invention provides the desirable feature of treating the leather in some conditions in small units, so that the heat can be uniformly applied and so that the containers can be readily handled.

15 It also provides a ready means of conveying away the by-product gases without permitting the access of air to the leather when being treated.

It will be apparent that there may be a variety of modifications of the furnace, containers and piping, but we desire to comprehend within our invention such suitable modifications to meet varying conditions.

We have found the foregoing to be the preferable method of handling and arranging such apparatus when following the batch method of our process for producing our product. It is obvious that the pipe may be suspended by hangers from the roof of the oven, so that only certain portions of it need to be moved when the containers are detached and removed from the oven.

The containers are divided in halves so that when they are closed the flanges 27 will abut.

20 Having thus fully described our invention, what we claim as new and desire to secure by Letters Patent, is:

1. In an apparatus of the character described, an oven chamber having a floor with a chamber for circulation of gases below the floor and contiguous thereto, a furnace at the rear of said oven chamber with means communicating the furnace with the upper part of the oven chamber and flues at the front of the oven chamber connecting the interior of the oven chamber with the chamber below the oven chamber floor, an escape stack for the heated gases connected with the chamber be-

low the floor at the rear of the oven chamber, a system of piping in the upper part of the oven chamber, and detachable means for connecting the piping system to containers and a conduit communicating with said piping and leading to the outside of the oven chamber.

2. In an apparatus of the character described, an oven chamber having a floor with a chamber for circulation of gases below the floor and contiguous thereto, a furnace at the rear of said oven chamber with means communicating the furnace with the upper part of the oven chamber and flues at the front of the oven chamber connecting the interior of the oven chamber with the chamber below the oven chamber floor, an escape stack for the heated gases connected with the chamber below the floor at the rear of the oven chamber, and a system of pipes in the upper part of the oven chamber leading to the outside and closed to the air of the oven chamber, and containers within the oven chamber also closed to the air of the oven chamber and attachable to the pipes.

3. In an apparatus of the character described, an oven chamber having a floor with a chamber for circulation of gases below the floor and contiguous thereto, a furnace at the rear of said oven chamber with means communicating the furnace with the upper part of the oven chamber, flues at the front of the oven chamber connecting the interior of the oven chamber with the chamber below the oven chamber floor, an escape stack for the heated gases connected with the chamber below the floor at the rear of the oven chamber, said oven chamber containing a system of piping closed to the air of the oven chamber, and sealed containers within the oven chamber in communication with the piping system each of said containers comprising upper and lower sections with means for clamping the sections together.

In testimony whereof, we affix our signatures.

STANLEY B. MATHEWSON.
WALTER K. JAMISON.
